UNITED STATES PATENT OFFICE.

OLIVER C. DENNIS, OF CHICAGO, ILLINOIS.

ELECTRIC VULCANIZER.

1,147,847.

Specification of Letters Patent. Patented July 27, 1915.

Application filed July 20, 1914. Serial No. 851,865.

To all whom it may concern:

Be it known that, I, OLIVER C. DENNIS, a resident of Chicago, in the county of Cook and State of Illinois, have invented certain new and useful Improvements in Electric Vulcanizers, of which the following is a full, clear, and exact description.

The invention relates to electric vulcanizers.

10 Electrical vulcanizers as heretofore constructed were usually so cumbersome that they have gone into use only in shops.

15 The present invention designs to provide a portable electrical vulcanizer which is small and compact so that it may be carried on a motor-vehicle for road-side repairs if necessary, and which is adapted to be operated by current of a low voltage (usually six volts) which is available from the storage battery carried on the vehicle and used for lighting and ignition.

20 A further object of the invention is to provide an improved portable electric vulcanizer in which provision is made to automatically prevent overheating or burning of the rubber.

25 A further object of the invention is to provide an improved electrical vulcanizer which is adapted to cut off the supply of current as soon as the maximum temperature desired in vulcanization is reached, so that the work may be placed in the vulcanizer and left without further attention and without the necessity of waiting for the patch to be vulcanized before operating a switch to cut off the current and discontinue the vulcanizing operation.

30 A further object of the invention is to provide an improved electrical vulcanizer which is adapted to patch inner tubes and casings of tires.

35 A further object of the invention is to provide an improved electrical vulcanizer in which the resistance element is secured in the case, so that it will not become broken when carried about on the vehicle.

40 Lastly, the invention is designed to provide a portable electric vulcanizer of improved construction.

45 The invention consists in the several

novel features hereinafter set forth and more particularly defined by claims at the conclusion hereof.

In the drawings, Figure 1 is a plan of the improved vulcanizer. Fig. 2 is a side elevation. Fig. 3 is a section taken on line 3—3 of Fig. 1. Fig. 4 is a plan, the case being shown in section. Fig. 5 is an enlarged sectional plan of the automatic cut-out switch. Fig. 6 is a section taken on line 6—6 of Fig. 5. Fig. 7 is a detail section taken on line 7—7 of Fig. 5.

The improved vulcanizing device comprises a case 10, which is provided with laterally projecting arms or lugs 11 having slotted ends, and a clamping-plate 12 provided with screws 14 which are adapted to be secured by nuts 15 in position to clamp a tire-tube and patch in firm contact with and against the bottom plate 16 of the case. 70 The top face 17 of the case is curved to fit against a tire casing so that a patch may be vulcanized on the casing when the case 10 is secured to the casing by suitable means. The vulcanizer is thus adapted to repair 75 either inner tubes or casings. The concave wall 17 and the side wall 18 of the case are integral and form a box or receptacle for the heating element. Bottom plate 16 is removably secured to the plate by screws 19. 80

The heating element comprises a strip of suitable resistance wire 20 which is wound around a sheet of mica or other suitable insulating material 21 which is notched, as at 22, to hold and space the coils. Binding- 85 posts 23 and 24 are secured in, pass through, and are insulated from, the sides of case 10. These binding posts are adapted for connection to flexible conductors 25 and 26 which are adapted to be connected to the poles of 90 the usual six voltage storage battery of a motor vehicle. A switch chamber 27 is formed in one corner of the case by an inset angular partition or wall 28, and a plate 29 is secured to the side walls of the case by 95 screws 30 for closing said chamber. The chamber contains the controlling mechanism whereby the circuit will be interrupted when the desired vulcanizing temperature, usually from 250° to 280°, is attained. One end of 100

resistance wire 20 is connected to binding post 24 and its other end is connected to a binding post 31 which is secured in and extends through wall 28. The heating element 5 also comprises a strip of resistance wire 32 which has one of its ends connected to binding post 23 and its other end to a binding post 33 which is also secured in, extends through and is insulated from wall 28.

10 The heating element which consists of strips of wires 20, 32, is formed of about 20 gage resistance wire used for heating coils, and it has been found by experiment that approximately two feet of such wire will, 15 when supplied with six volt current, raise the temperature of the vulcanizer to about 260 to 280° Fahr. in about ten minutes. One corner of the mica sheet 21 is cut away as at 34 to clear the inset wall 28 and resistance wire 32 is also wound around said sheet. The mica sheet 21 and resistance wires are embedded in refractory material 21', such as fire-brick, which completely fills the space in the case 10. This material is 20 placed in the case in a plastic condition and when set will form a solid packing around all portions of the mica sheet and resistance-wires to prevent them from being broken by vibration incident to carrying the device on 25 a motor vehicle. This refractory material also distributes the heat from the resistance wires to all portions of the case, and also retains the heat so the vulcanizer will cool slowly and continue the vulcanizing process 30 for a period after the current has been cut off.

A switch is provided for connecting the circuit between binding posts 31 and 33 so that the resistance elements 20 and 32 will 40 be connected in series. This switch may be operated manually to close the circuit through the heating wires, and when the correct vulcanizing temperature has been reached, usually about 250° to 285° Fahrenheit, the switch will be automatically released 45 to open the circuit and permit the vulcanization to be completed by the residual heat in the refractory material and case. This switch consists of a spring contact-strip 36 which is adapted to contact with and engage 50 a ratchet-wheel 37. Contact 36 is secured to a plunger 38 which is slidably mounted in a bracket 39 which is electrically connected to binding post 31 and insulated from 55 the case. A button 41 of insulating material is secured to the plunger and extends through and is guided in one of the sides of the case, so that it can be manipulated from the outside thereof. A spring 40 is applied to hold 60 button 41, plunger 38, and spring-contact 36 normally in position so that the circuit will be interrupted. Button 41 has a stop-flange 41' which limits the outward movement of the button by spring 40. Spring

contact 36 is provided with a slot 42 adapted 65 to receive a tooth of ratchet-wheel 37 when the button 41 is pushed inwardly, to latch the contact in position to close the circuit. Ratchet-wheel 37 is electrically connected to binding post 33 and is mounted on a pin 70 43 held in the inner bifurcated end of binding post 33. The upper face of ratchet 37 is covered with soft solder as at 44 and a hole 45 is formed in binding post 33 which is also filled with soft solder. The binding-post is formed of material which will unite with the solder.

The operation of the device will be as follows: Assuming conductors 25 and 26 to have been connected to the battery of the 80 motor vehicle and the case 10 to be secured in contact with the work or patch to be made, it is only necessary for the operator to push the button 41 inwardly which will cause the inner end of spring 36 to spring 85 over and lock on one of the teeth of ratchet 37. Thereupon, a circuit will be established as follows: from battery to conductor 25, binding post 24, resistance wire 20, binding post 31, bracket 39, plunger 38, spring contact 36, ratchet-wheel 37, binding post 33, resistance wire 32, binding post 23, conductor 26, to battery. The resistance element 20 being formed of such length and wound of unusually large wire so as to have 90 a low resistance, will permit sufficient current to flow through the wire to cause it to be heated by six volt current usually available on a motor-vehicle. The circuit will remain closed and the resistance wires will 95 heat the case and the refractory material therein until the temperature reaches a point which will soften the solder between ratchet 37 and binding-post 33 which will, under the tension of the spring 40, rupture or shear 100 the soldered connection between the face of the ratchet 37 and the solder plug in hole 45, and thereupon spring 40 will retract plunger 38 and spring-contact 39, the ratchet being 105 rotated a short distance as the contact is withdrawn. This disconnection will open the circuit and discontinue the heating operation. The soft solder used for the connection between ratchet 37 and post 33 is of such character that it will melt when the temperature 110 at which the current should be cut off is reached.

As soon as the device cools sufficiently to cause the solder to harden, ratchet wheel 37 will again be automatically secured and resoldered to binding post 33 so that when button 41 is again pushed inwardly, the circuit will be again closed as heretofore described. The position of button 41 indicates whether the vulcanizing operation has been completed or not. If under special circumstances, a longer period of vulcanization than the predetermined one is desired, the 115 120 125

button 41 may be held inwardly manually after it has been released and before resoldering has taken place.

The invention thus exemplifies a portable 5 electric vulcanizer which is adapted to be carried on a motor vehicle and operated by the low voltage battery usually present for other purposes. It is impossible to burn the work, because of the automatic cut-off which 10 must be reset manually before the device will be again heated after it reaches the point desired. The device in its entirety is peculiarly adapted to be carried on the motor vehicle for road-side use, if necessary. The 15 device can be manufactured at a low cost and is less dangerous to handle than the portable open flame vulcanizers which are now used for road-side repairs. The vulcanizer is self contained and all of the operating parts are 20 disposed in the case, so that it is particularly well adapted to be carried on a motor-vehicle. The refractory material which fills the chamber in the case distributes the heat to the top and bottom walls of the case so 25 that either of said walls may be used for vulcanizing, and furthermore, by providing such a filling, the heating element will not be broken by vibration or shock to which it may be subjected when the device is carried 30 on a motor vehicle. By disposing the switch and fusible connection in a chamber in the case the heat will be conducted thereto from the resistance element and there are no parts on the outside of the case which are likely 35 to become broken.

The invention is not to be understood as restricted to the details set forth, since these may be modified within the scope of the appended claims without departing from the 40 spirit and scope of the invention.

Having thus described the invention, what I claim as new and desire to secure by Letters Patent, is:

1. In a portable electric vulcanizer, the 45 combination of a case, an electrical resistance element in the case, a switch for controlling the current to said element, and a fusible automatically resoldering connection controlling the operation of the switch and 50 fusible at the vulcanizing heat.

2. In a portable electric vulcanizer, the combination of a case, an electrical resistance element in the case, a switch for controlling the current to said element, a fusible automatically resoldering connection controlling the operation of the switch and fusible at the vulcanizing heat, and means whereby the switch may be closed manually, said resoldering connection controlling the opening 55 of the switch, to cause the flow of current to said element to be discontinued until the switch is again manually operated.

3. In a portable electric vulcanizer, the combination of a case, an electrical resist-

ance element in the case, a switch for controlling the current to said element, and a fusible automatically resoldering connection controlling the operation of the switch, said connection releasing the switch under a shearing action when fused. 65

4. In a portable electric vulcanizer, the combination of a case, an electrical resistance element in the case, a switch for controlling the current to said element, and a fusible automatically resoldering connection 70 controlling the operation of the switch and fusing under vulcanizing heat, said connection releasing the switch under a shearing action when fused. 75

5. In a portable electric vulcanizer, the combination of a case, an electrical resistance element in the case, a switch for controlling the current to said element embodying a spring retracted plunger, and a ratchet wheel with which said plunger engages 80 when projected to close said circuit, and a fusible automatically resoldering connection 85 between said ratchet wheel and its support, said connection releasing said ratchet wheel under a shearing action when fused. 90

6. In a portable electric vulcanizer, the combination of a case, an electrical resistance element in the case, a switch for controlling the current to said element embodying a spring retracted plunger, and a ratchet 95 wheel with which said plunger engages when projected to close said circuit, and a fusible automatically resoldering connection between said ratchet wheel and its support and fusing under vulcanizing heat, said 100 connection releasing said ratchet wheel under a shearing action when fused.

7. A portable electric vulcanizer comprising a case, an electrical resistance element mounted therein and adapted to be operated 105 by a current of low voltage to heat the case to the vulcanizing point, and comprising a plurality of strips, and a switch between the strips for connecting them in series, said switch operating when opened to break the 110 circuit to both of said strips.

8. A portable vulcanizer, comprising a case having a wall adapted to be applied to the work to be vulcanized, a partition dividing the same into two chambers, an electrical resistance element in one chamber of the case, and a switch disposed in the other chamber and adapted to be operated from the outside of the case to render the resistance element operative. 115

9. In a portable electric vulcanizer, the combination of a case, an electrical resistance element in the case, a switch for controlling the operation of said element and a fusible automatically resoldering connection disposed in the circuit and controlling 120 the operation of the switch.

10. In an electrical vulcanizer, the com-

bination of a case, an electric resistance ele-
ment in the case, a switch for controlling
the operation of said element comprising a
spring contact, means for operating the
5 switch comprising a ratchet engaged by
said contact, and a fusible connection for
the ratchet.

11. In a vulcanizer, the combination of a
case, a resistance element in the case, a
10 switch for controlling the operation of said

element comprising a spring-contact, switch-
controlling means comprising a ratchet en-
gaged by said contact, and a fusible connec-
tion directly engaging and retaining the
ratchet.
